DESIGN FOR A BROOCH PIN OR SIMILAR ARTICLE

Ernest Steiner, New York, N. Y.

Application March 22, 1937, Serial No. 68,315

Term of patent 7 years

To all whom it may concern:

Be it known that I, Ernest Steiner, a citizen of the United States and residing at New York, in the county of New York and State of New York, have invented a new, original, and ornamental Design for a Brooch Pin or Similar Article, of which the following is a specification, reference being had to the accompanying drawing, forming part thereof, and in which

Fig. 1 is a front view of a brooch showing my new design;

Fig. 2 is a side view upon the line 2—2 of Fig. 1, and

Fig. 3 is a top view upon the line 3—3 of Fig. 1.

The characteristic feature of the design consists of a bow made of metal strips in combination with a cluster or group of globular or bead-like elements.

I claim:

The ornamental design for a brooch pin or similar article as shown and described.

ERNEST STEINER.
